Attorney

UNITED STATES PATENT OFFICE.

ERVIN V. SWEET, OF ATTLEBORO, MASSACHUSETTS, ASSIGNEE TO C. O. SWEET AND SON COMPANY, A CORPORATION OF MASSACHUSETTS.

SEPARABLE FASTENER.

Application filed June 24, 1922. Serial No. 570,562.

To all whom it may concern:

Be it known that I, ERVIN V. SWEET, a citizen of the United States, residing at Attleboro, in the county of Bristol and State 5 of Massachusetts, have invented certain new and useful Improvements in Separable Fasteners, of which the following is a specification.

My invention relates to separable fasteners for guards, garters, armlets and the like and has for its essential objects the avoidance of drawing the article upon the body into desired location; the speedy application of the article to the body and its quick and 15 facile release; concealment of the fastening mechanism; and security, simplicity and inexpensiveness.

To the above ends essentially my invention consists in such parts and in such 20 combinations of parts as fall within the scope of the appended claims.

In the accompanying drawings which form a part of this specification,

Figures 1 and 2 are a front and plan elevation respectively of my novel invention,

Figure 3, a section on line 3—3 of Figure 1, and

Figure 4, a section on line 4—4 of Figure 3.

Like reference characters indicate like parts throughout the views.

My fastener is in this case attached to a strap or ribbon 6 of cloth, leather or other flexible material carrying near one end a 35 slidable buckle 7 and fixed thereto by an end loop 8 to form an attaching loop 9. The opposite end of the strap or band 6 has a loop 11. This passes through a marginal slot 12 in a plate 13 that has fast in its central portion a post 15 provided with a head 16.

The loop 9 passes through a slot 18 in a lateral lug 19 upon the margin of a back plate 20 engaged with a face plate 21 by a 45 bent over peripheral flange 23, and provided with a central depression 24. Sealed in the depression is a socket plate 25 having a peripheral bead 27 and a central socket housing 30 in alignment with a hole 31 in the back plate portion 21 and having lateral 50 slots 33. The socket member is rigidly held in position by the portion 24 of the back

plate engaging the plate 25, and by the engagement of the housing 30 with the front plate. A curved wire spring 35 is fitted in 55 the socket plate below the rib 27 having reversed bends 37 and 38 and terminating in parallel arms 40 entering the slots 33 to engage the post 15 in the rear of the head 16 which is adapted to register in the end of 60 the socket 30.

To attach or detach the described device to the arm or leg it is necessary only to snap the post into or withdraw the same 65 from the socket manually.

I claim:

1. In a separable fastener, an attaching plate provided with a slot, a post on the plate, a head on the post, a back plate provided with a marginal slot and provided 70 with a central depression and with a central hole, a front plate fast to the back plate, and a socket member embraced by the front plate and back plate in alignment with the hole and adapted to receive the head.

2. In a separable fastener, an attaching plate provided with a slot, a post on the plate, a head on the post, a back plate provided with a marginal slot and provided 80 with a central depression and with a central hole, a front plate fast to the back plate, a socket member between the front plate and back plate in alignment with the hole and provided with lateral slots, and a spring between the front plate and the back plate engageable with the post through the slots.

3. In a separable fastener, an attaching plate provided with a slot, a post on the plate, a head on the post, a back plate provided with a marginal slot and provided 85 with a central depression and with a central hole, a front plate, a peripheral flange on the front plate engaging the back plate, a socket plate seated in the depression, a socket housing integral with the center of 90 the socket plate in alignment with the hole and provided with lateral slots, and a spring carried by the socket plate comprising an arcuate body portion, and parallel arms seated in the slots engageable with the post.

In testimony whereof I have affixed my signature.

ERVIN V. SWEET.
